Des. 192,017
Patented Jan. 2, 1962

192,017

UTENSIL LID RACK OR SIMILAR ARTICLE

Charles Gregg Moore, Wooster, Ohio, assignor to Rubbermaid Incorporated, Wooster, Ohio, a corporation of Ohio

Filed July 21, 1961, Ser. No. 66,012

Term of patent 14 years

(Cl. D44—29)

FIG. 1

FIG. 2

FIG. 3

FIG. 1 is a plan view of a utensil lid rack or similar article embodying my new design.

FIG. 2 is a side elevation thereof.

FIG. 3 is an end elevation thereof.

I claim:

The ornamental design for a utensil lid rack or similar article, substantially as shown.
